No. 792,269.

PATENTED JUNE 13, 1905.

A. H. JACKSON.
COMPOSITE RAILWAY TIE.
APPLICATION FILED JAN. 16, 1905.

UNITED STATES PATENT OFFICE.

AMOS H. JACKSON, OF FREMONT, OHIO.

COMPOSITE RAILWAY-TIE.

SPECIFICATION forming part of Letters Patent No. 792,269, dated June 13, 1905.

Application filed January 16, 1905. Serial No. 241,287.

To all whom it may concern:

Be it known that I, AMOS H. JACKSON, a citizen of the United States, residing at Fremont, in the county of Sandusky and State of Ohio, have invented certain new and useful Improvements in Composite Railway-Ties; and I do hereby declare the following to be a full, clear, and exact description of the invention, such as will enable others skilled in the art to 10 which it appertains to make and use the same.

This invention relates to that class of railway cross-ties commonly known as "composite" ties; and it consists of the novel arrangement and combination of the several 15 parts, as will be hereinafter fully described in this specification and briefly stated in the claims.

One of the principal objects of the invention is to produce a railway-tie sufficiently 20 strong and durable to withstand the wear and tear to which it may be subjected by passing trains and that will not be affected by climatic changes.

Other objects of the invention will become 25 apparent upon a detailed description thereof.

In the drawings, Figure 1 is a longitudinal vertical section of my improved tie; Fig. 2, a top plan view thereof; Fig. 3, a transverse section on line xx of Fig. 1; Fig. 4, a longitudinal vertical section of a modified form of 30 my improved tie; and Fig. 5, a transverse section on line yy of Fig. 4, showing modified form of strengthening member and tie member.

Referring to the several views, the numeral 35 1 indicates the body of my improved tie, which is preferably composed of concrete or a mixture of hydraulic cement, sand, and water. The body may be of any desired shape and is formed with a transverse groove or recess 2 40 near each end thereof to provide a seat for the rail. Inclosed in the body are two metallic strengthening members 3 3, arranged parallel with each other and longitudinally 45 of the body. The respective ends of these members preferably curve upward and projecting through the upper surface of the body form abutments 4, against which the outer flanges of the rails 5 abut. Also embedded 50 in the body in line with the inner wall of the

grooves 2 are headed bolts 6, which pass up through anchor-plates 7, arranged transversely beneath the strengthening members. The screw-threaded ends of the bolts project slightly above the upper surface of the body 55 and being in line or flush with the inner walls of the grooves 2 form, in conjunction with the abutments 4, rigid side supports for the rails. Arranged centrally within the body and in line with the bottom of the grooves 2 is a metallic tie member 8, having a perforation 9 near each end for the passage of bolts 10, which are embedded in said body, as shown in Figs. 1 and 2.

To give additional strength and tenacity to 65 the tie, I prefer to embed therein a binder 11 of closely-woven wire fabric or a network of any suitable material, as shown in Figs. 1 and 3.

In constructing a road with my improved tie a cushion 12, of suitable material, preferably wood, is placed in each groove or recess and the rails laid thereon. Clamping-plates 13 and nuts 14 are employed to firmly secure 70 the rails in their seats.

It will be evident that ties constructed as herein described may be employed to replace old and worn-out wooden ties, and it will also be evident that "spreading" of the rails will be prevented, as the strengthening members 80 and the tie members and their bolts firmly and rigidly hold the rails against lateral movement.

In the modification shown in Fig. 4 the 85 curved ends and abutments of the strengthening members are dispensed with and plain straight members 15 are employed, and instead of the tie member being arranged centrally two tie members 16, only one being shown, are used, one arranged above each 90 strengthening member. Bolts 17 are embedded in the body in line with both the inner and outer side walls of the grooves or recess 2, which bolts pass up through holes in anchor-plates 18 and through holes in the tie members, clamping-plates 19 and nuts 20 being 95 used to secure the rails in their seats.

The strengthening members may be of any preferred shape in cross-section, either rectangular, as shown in Fig. 3, or angular, as 100

shown at 21, Fig. 5. In the latter form the anchor-plates may be dispensed with and the bolts passed through holes in the strengthening members, as shown in said Fig. 5. Tie-
5 rods 22 may be substituted for the tie members, in which case each end would be bent outwardly to form a hook 23 to engage the outer bolts.

Various modifications or changes in the de-
10 tails of construction of my improved tie may be made without limiting the scope of the in-
vention or changing the character thereof.

Having thus fully described my invention, what I claim, and desire to secure by Letters
15 Patent, is—

1. A railway-tie, composed of a body of con-
crete, or similar material, two strengthening
members and one or more tie members em-
bedded in said body, said members being ar-
20 ranged longitudinally and parallel with each
other, and securing-bolts embedded in the
body and passing through the tie member or
members.

2. A railway-tie, composed of a body of con-
25 crete, or similar material, two strengthening
members and one or more tie members em-
bedded in said body, said members being ar-
ranged longitudinally and parallel with each
other, securing-bolts embedded in the body
30 and passing through the tie member or mem-
bers, and a binder embedded in said body.

3. A composite railway-tie, consisting of a
body of suitable material, having a rail-seat
provided at each end, two strengthening mem-
35 bers and one or more tie members embedded
in said body, said members being arranged
longitudinally and parallel with each other,
and securing-bolts embedded in the body and
arranged in line with the outer and inner walls
40 of the rail-seats.

4. A composite railway-tie, consisting of a

body of suitable material, having a rail-seat
at each end, two strengthening members and
one or more tie members and their bolts em-
bedded in said body, said members being ar-
45 ranged longitudinally and parallel with each
other, securing-bolts embedded in the body
and arranged in line with the inner and outer
walls of the rail-seats, and a binder embedded
in said body.

5. A composite railway-tie, consisting of a
body of concrete, or similar material, having
rail-seats formed therein, two strengthening
members having upwardly-curved and abut-
ting ends, said abutting ends being in line
55 with the outer wall of the rail-seats, securing-
bolts arranged in line with the inner wall of
the rail-seats, a centrally-arranged tie mem-
ber, and securing-bolts arranged in line with
the outer wall of said rail-seats and the abut-
60 ing ends, all of said members and bolts be-
ing embedded in the body, as set forth.

6. A composite railway-tie, consisting of a
body of concrete, or similar material, having
rail-seats formed therein, two strengthening
members having upwardly-curved and abut-
ting ends, said abutting ends being in line
65 with the outer wall of said rail-seats, anchor-
plates arranged beneath the strengthening
members, securing-bolts arranged in line with
the inner wall of the rail-seats, a centrally-ar-
ranged tie member, and securing-bolts ar-
70 ranged in line with the outer wall of said rail-
seats and abutting ends, all of said parts be-
ing embedded in the body, as set forth.

In testimony whereof I affix my signature in
the presence of two witnesses.

AMOS H. JACKSON.

Witnesses:

H. F. MURPHY,
J. R. NOTTINGHAM.
